UNITED STATES PATENT OFFICE.

LEON L. RUSSELL, OF LIVERMORE FALLS, MAINE.

GAME.

Application filed June 14, 1927. Serial No. 198,782.

This invention relates to game apparatus of that type in which a rolling object is caused to follow a predetermined course by manual manipulation of the game board. 5 The present invention has for its object the provision of a game board over which rolling objects are to be successively moved through shifting of the board so as to follow the course of the circuits in a radio receiving set. The invention also has for its object the provision of means whereby the objects which have traveled over their respective prescribed courses may be held at the several points of their destinations until 10 all of the objects have been successfully manipulated and then all of the objects simultaneously released to be caught in a receptacle below the game board. The invention is illustrated in the accompanying drawings and will be hereinafter fully set forth. 15 20

In the drawings:

Figure 1 is a plan view of a game apparatus embodying my present invention;

25. Fig. 2 is a longitudinal section on the line 2-2 of Fig. 1;

Fig. 3 is a transverse section on the line 3-3 of Fig. 1, and

Fig. 4 is a bottom plan view with parts 20 in section on the line 4-4 of Fig. 3.

The game board 1 is a flat plate of any desired dimensions and of rectangular outline, said board being equipped at one end with an eye or other form of handle member 2. In the upper surface of the board 1 is formed a groove or channel having several branches and constituting a guide and hazard prescribing the path of the several rolling objects one of which is shown at 3. The channel or groove which defines the paths for the several objects has one end, 4, disposed at the upper left hand corner of the board and extends for a short distance parallel with the adjacent end edge of the board. At the said end of the channel or groove the letter A is marked, this end of the channel representing the antenna or aerial in the radio receiving circuits. From the lower end of the end portion 4, the channel extends toward the right and upwardly at an acute angle, as shown at 5, and from the inner end of this obliquely disposed portion a straight branch 6 extends toward the lower edge of the board and terminates in an opening 7 adjacent which the letter G appears representing the

ground connection of the set. The opening or pocket 7 extends entirely through the board and has a diameter approximately equal to the diameter of the ball or rolling object 3. The branch 6 represents the inductance coil having three turns represented by the arcuate branches 8 each communicating at both its ends with the straight branch 6 and having an upstanding oval-shaped lug or block 9 disposed therein whereby to cooperate with the arcuate wall of the channel to define the path which the rolling object must follow. From the lower end of the straight branch 6, a branch 10 extends parallel with the lower edge of the board and at its terminal is provided with an opening or pocket 11 extending therethrough and representing the A battery of the radio receiving set. The said pocket 11 is of the same form and dimensions as the first-mentioned pocket 7 and is located at the extreme end of the branch channel 10. From the lower side of the said branch channel 10 at a point in advance of the pocket 11, a branch 12 extends downwardly and then toward the right hand end of the board and then upwardly parallel with said end to reach a pocket or opening 13, said pocket or opening representing one of the telephone receivers. It will be noted that the branch channel 12 passes around the end of the channel 10 and around the pocket representing the A battery. Between the ends of the channel 10, a vertical channel 14 extends upwardly from the upper wall of said channel 10 to a point near the upper edge of the board where it is turned to the right, as shown at 15, and merges into a large circular chamber or recess 16 representing the tube of the radio set. Between the ends of the vertical channel 14, offsets 17 are formed in the side walls thereof and in the bottom of each offset is an opening or pocket 18, these openings or pockets representing one condenser and a suitable legend C' being placed upon the board adjacent either offset. Similar offsets 19 are formed in the upper and lower walls of the branch channel 15 and pockets 20 are formed through the bottom of these offsets to represent a second condenser which is indicated by the legend C² upon the board. Lines 21 may be marked upon the surface of the board between the recess 16 and the channels 10 and 11 to represent the electrical connections between the tube and the A battery.

so as to accentuate the simulation of a radio receiving set. From the upper side of the recess or chamber 16, a channel 22 extends tangentially therefrom toward the right hand edge of the board and is then carried downwardly, as indicated at 23, in alignment with the terminal leg of the branch 12, a pocket or opening 24 being provided at the end of said channel 23 to represent one of the telephone receivers. Intermediate the ends of this branch 23, a pocket or opening 25 is formed through the bottom of the same and this pocket or opening represents the B battery.

On the under side of the game board there is secured a bracket 26 which extends lengthwise of the board and is considerably shorter than the board, the upper edge of this bracket being recessed or longitudinally notched, as indicated at 27, thereby defining end lugs 28 whereby the bracket is secured to the board while the greater portion of its upper edge is spaced from the board. Secured rigidly to the bracket at the center thereof and depending therefrom is a post 29 having its lower end rotatably mounted in a support 30 consisting of a bar or bracket secured to and extending between the side plates 31 of a supporting base which includes an inclined top plate 33 through which the post passes. At the lower end of the top plate 33, a pocket or depression 34 is formed therein and at the said end of the plate on the upper surface thereof are provided ribs 35 which converge toward the said pocket and thereby direct the rolling objects into the pocket, it being understood that the several balls or other rolling objects are retained in their pockets until all of the balls have been manipulated and are then permitted to drop onto the top plate 33 of the supporting base and thereupon roll into the receptacle 34 where they are held until another player has his turn in the game. To retain the balls in the pockets, there is provided a retaining plate 36 which is slidably mounted against the under side of the board 1 and is constructed with a large longitudinally extending opening 37 which permits the board to clear the lugs 28 of the bracket 26. At the opposite sides of this opening 37, the retaining plate is also constructed with longitudinally extending slots 38 through which headed pins or screws 39 are inserted into the board to support the retaining plate on the board and at the same time permit a limited sliding movement thereof. At the right hand end of the retaining plate 36, there is provided a loop or handle 40 and adjacent said handle a contractile spring 41 is extended between and secured to the retaining plate and the adjacent end of the bracket 26, as clearly shown in Figs. 3 and 4. It will thus be seen that the retaining plate is normally held in the position

illustrated in the drawings and that by grasping the handles 2 and 40 the player may turn the board pivotally so that the inclination of its surface will be varied and the travel of the rolling object or ball 3 through the several channels may be controlled. On the inner side wall of the opening 37, a projection 42 is provided of proper size and form to normally extend under the offsets 17 and across the pockets 18 therein so that it will support a ball which may happen to drop into either of said pockets and adjacent the said projection notches 43 are provided in the wall of the opening 37 so that when the retaining plate is shifted against the influence of the spring 41 the pockets 18 will be opened and the objects therein permitted to drop onto the top plate 33 of the supporting base. The material of the retaining plate normally extends over the other pockets of the game board, as will be understood upon reference to the dotted lines in Fig. 4, but through the retaining plate, openings 44 are provided and so located that upon drawing out the retaining plate all the pockets will be uncovered and the balls caught therein will be discharged, the end of the opening 37 performing this office for the pockets representing the telephone receivers.

From the foregoing description, taken in connection with the accompanying drawings, the manner of using the apparatus will, it is thought, be readily understood. Five balls 3 are provided and they are placed in the recess or pocket 34 until they are to be manipulated by a player. The first ball is placed in the end portion 4 of the channel in the game board and is to travel from the aerial to the pocket 7 representing the ground, such travel being effected by turning the board about its pivot in order to cause the ball to roll by gravity over the desired path. This first ball represents the ground connection and must pass direct from the aerial to the ground pocket without passing into or around any of the turns 8 representing the coil and the player may have three trials to accomplish the desired object, provided the ball does not pass into any of the coils, passing of the ball into one of the coils causing the player to lose his turn. The second ball to be played represents the A battery and this ball must pass from the aerial to the A battery without passing into any of the turns of the coil or into any other pocket, while the third ball represents the B battery or the other part of the internal energy and must pass from the aerial to the B battery without passing into any of the turns of the coil or into any of the condenser pockets. The fourth ball played represents a part of the external energy absorbed by the aerial and must pass from the aerial into the upper and out of the lower side of each

turn of the coil and then pass to the pocket 24 representing the upper side of the telephone receiver. This ball must not drop into any of the condenser pockets and must 5 pass over the B battery, the passage over the B battery, however, being easily effected inasmuch as the previously manipulated ball will be in said pocket and fill the same. The fifth ball represents the other part of the 10 external energy absorbed by the aerial and must pass through the several turns of the coil and then to the lower pocket of the telephone receiver and must not enter any other pocket. Each player may have three 15 trials for each ball, provided the ball does not stop in any of the condenser pockets, in which event he will lose his turn. After all the balls have been played, the retaining plate is drawn out, whereupon the balls will 20 at once drop onto the top plate of the supporting base, as previously described.

The rules for scoring may, of course, be varied more or less but, as an example, it may be said that if a player plays all the 25 balls correctly he may score five points for each of the balls representing the ground, A battery, and the B battery, and ten points for each of the balls representing the telephone, making a total possible score of 30 thirty-five points. If the player places the ground ball and the two battery balls properly without error and then in playing the upper telephone ball should permit said ball to drop into one of the condenser 35 pockets, he will lose his turn and can score only for the ground and the A battery, the B battery ball not counting.

My game apparatus is very simple and can be easily manipulated and will be productive of considerable amusement and will 40 also prove instructive. Considerable skill may be acquired in manipulating the board and as more skill is acquired, will prove more interesting to those engaged in playing the 45 game.

Having thus described the invention, I claim:

1. A game apparatus comprising a board disposed in an inclined position and mounted 50 for pivotal movement and provided in its upper surface with a channel and series of branch channels and having pockets formed therethrough at various points in the several channels, rolling objects to travel through the channels and enter selected pockets, and means on the under side of the board to temporarily retain the balls in the pockets.

2. A game apparatus comprising a game board inclined from top to bottom and 60 mounted for pivotal movement, said board having a channel and branch channels in its upper surface and having pockets at various points in the several channels, a rolling object to travel through the several chan-

nels and enter a selected pocket, a retaining plate mounted on the under side of the board to hold the ball in the pocket, means for yieldably holding the retaining plate in ball supporting position, the game board having a handle at one end and the retaining plate 70 having a handle at the opposite end of the board whereby manipulation of the board may be effected..

3. A game apparatus comprising a game board provided in its upper surface with channels and branch channels and having open bottom pockets formed at various points in the bottoms of the channels, said channels and pockets representing elements in a radio receiving set, a ball to travel 75 through the channels and enter a selected pocket, a retaining plate slidably mounted on the under side of the board to temporarily hold the ball in a selected pocket and having openings therethrough to register 80 with the pockets in the board whereby a ball in any pocket may be discharged, and yieldable means holding the plate normally in ball-supporting position.

4. A game apparatus comprising a game 90 board mounted for movement about a tilted pivot and provided in its upper surface with a channel and branch channels and having pockets formed at various points in the bottoms of the several channels, a retaining 95 plate slidably mounted on the under side of the game board and having openings therethrough adapted to register with the pockets in the game board, means for yieldably holding the retaining plate across the pockets, 100 and handle members at opposite sides of the apparatus one on the game board and one on the retaining plate whereby the apparatus may be manipulated.

5. A game apparatus comprising a supporting base having an inclined top plate and provided with a receptacle at the lower end of said top plate, a board mounted for pivotal movement in a plane parallel with the top plate and provided with pockets, 110 and a rolling object to travel over the board and pass through a pocket onto the top plate.

6. A game apparatus comprising a supporting base, a board having a pivot post secured to its under side and rotatably 115 mounted in the supporting base, the post being tilted with respect to the base and the game board being provided in its upper side with communicating channels and having pockets formed in said channels at various 120 points thereof, rolling objects to travel through the channels and each enter a selected pocket, and means on the under side of the board to temporarily retain the balls in the pockets.

In testimony whereof I affix my signature,

LEON L. RUSSELL, [L. s.]
